DESIGN FOR A STEMMED GOBLET

Elmer Bell, Mount Pleasant, Pa., assignor to
Bryce Brothers Company, Mount Pleasant, Pa.,
a corporation of Pennsylvania

Application February 1, 1938, Serial No. 74,791

Term of patent 14 years

To all whom it may concern:

Be it known that I, Elmer Bell, a citizen of the United States and residing at Mount Pleasant, in the county of Westmoreland and State of Pennsylvania, U. S. A., have invented a new, original, and ornamental Design for a Stemmed Goblet, of which the following is a specification, reference being had to the accompanying drawing forming a part thereof, wherein:

The figure is a view in elevation of a stemmed goblet illustrating my new design.

It is to be understood that my new design may be applied to a complete line of stemmed ware.

I claim:

The ornamental design for a stemmed goblet substantially as shown and described.

ELMER BELL.
